MEANS FOR IGNITING A TORCH UNDER WATER

Mario di Zoppola, New York, N. Y., assignor to
General Bronze Corporation, Long Island City,
N. Y., a corporation of New York

Application April 3, 1943, Serial No. 481,677

1 Claim. (Cl. 158—27.4)

This invention relates to a method of and means for promoting the ignition of a torch under water.

One of the objects of this invention is to provide a device for promoting ignition of a torch under water which is simple and inexpensive in construction, and at the same time sufficiently sturdy and durable to withstand the conditions under which it is used. Another object is to provide a device of the above nature, which is readily attachable to and detachable from the end of the torch. Another object is to provide a device of the above nature which may be interchangeably used with various types of torches. Another object is to provide a device of the above nature which is light and compact, and which may easily be installed on or attached to the end of the torch by the diver. Another object is to provide a method of lighting a torch while under water, by which the diver can quickly ignite the torch without danger to himself or his diving equipment. Other objects will be in part apparent and in part pointed out hereinafter.

The invention accordingly consists in the features of construction, combinations of elements, arrangements of parts, and in the several steps and relation and order of each of the same to one or more of the others, all as will be illustratively described herein, and the scope of the application of which will be indicated in the following claim.

In the drawing, wherein I have shown one form of my invention,

Figure 1 is a side elevation of a torch with my ignition promoting device attached thereto; and,

Figure 2 is an enlarged fragmentary sectional elevation of my ignition promoting device attached to the end of the torch.

Similar reference characters refer to similar parts throughout the various views of the drawing.

In making repairs to, or otherwise working on metallic objects under water, such as the hull of a sunken ship, for example, the diver very often has to cut away a part of the metal, and for this purpose he uses an oxygen-hydrogen torch, which is capable of burning under water. It frequently occurs that the torch flame is extinguished for one reason or another, and the customary practice under such circumstances is for the torch to be hauled above the surface of the water, re-ignited and then lowered to the diver for his continued use thereof. This, of course, results in loss of the diver's time, and also subjects him and his

air lines to a certain amount of danger from the ignited torch as it is relowered to him after being re-ignited. It is toward the end of saving the diver's time and eliminating these risks that my invention is directed.

With reference to Figure 1, a torch generally indicated at 10 comprises a handle, in one end of which is secured a band 12, to which is pivoted an operating lever 13. On the other end of handle 11 is a base 14 within which is installed an oxygen needle valve (not shown) which may be operated by a disc or nut 15, the stem of which extends through the base to the valve. Extending from base 14 is a short length of pipe 16, on which is threaded a hydrogen needle valve 17, operable by a disc or nut 18. Valve 17 includes a threaded extension 19, which may be attached to a flexible tube (not shown) leading to a source of hydrogen. The oxygen valve likewise has a threaded extension 20 to which may be attached the end of a flexible tube connected to a source of oxygen. A third pipe 21 leads into base 14 and carries at its other end an air valve 22, which may be controlled by a disc or nut 23.

Connected to the left-hand end of handle 11, as viewed in Figure 1, are pipes 24, 25 and 26, which are connected respectively to the hydrogen, oxygen and air inlets, and accordingly provide conduits for the flow of the oxygen and hydrogen

30 to a head or mixing chamber generally indicated at 27, wherein the two gases are mixed. The head 27 is attached to a nozzle 28 to which is fastened an L 29, to which the air pipe 26 is secured as by a union 30. As shown in Figure 2,

35 nozzle 28 has an inner chamber 31 within which is disposed a pipe or tube 32 which extends upwardly through the nozzle, and is connected to head 27 in any suitable manner so as to provide a passage for the flow of the mixed oxygen and hydrogen out of the end of the nozzle. Pipe or tube 32 is considerably smaller in diameter than chamber 31, and accordingly forms therewith a space 33 which communicates with L 29 and accordingly constitutes a conduit for the flow of air

40 through the nozzle. The exit end of the nozzle is provided with a suitable number of projections 34, which maintain the end surface 35 of the nozzle spaced slightly from the iron plate, for example, that is being cut. Through this space air rushes

45 while the torch is being used at sufficient pressure to prevent the entrance of water, which would extinguish the flame of the ignited oxygen and hydrogen.

The torch I have described hereinabove is of 50 well-known conventional construction, and in

and of itself does not constitute any part of my invention.

From a consideration of the above, it will be apparent that ignition of such a torch under water is impossible, as when the torch nozzle is held against the iron plate, for example, and the air and gas valves turned on, it would be impossible to introduce any ignition device near enough to the jet of oxygen and hydrogen to ignite it. Furthermore, the air pressure is such as would probably extinguish the spark of an ignition device before it could effectively ignite the jet. I have found, however, that by creating a static body of air, at a pressure substantially equal to the pressure of the surrounding water, adjacent the exit end of the torch nozzle, and applying the spark of an ignition device adjacent the outlet of pipe 32, the jet of mixed gases can readily be ignited by a suitable ignition device such as a spark plug, for example, after which the static body of air which keeps the water away from the flame, may be dispensed with.

To carry out my method, I illustratively provide a bell or the like, generally indicated at 36, which has a neck 37, provided with an interior shoulder 38 or the like. This shoulder supports a rubber washer 39 which is held on the shoulder by a bell-mouthed lock washer 40, adapted to be threaded into bell neck 37. The inner diameter of neck 37 is slightly larger than the outside diameter of nozzle 28, and rubber washer 39 is sufficiently thick so that its inner diameter is less than either the inner diameter of neck 37 or the outer diameter of nozzle 28, so that when the nozzle is forced into the bell neck, the rubber washer grips it firmly and effectively seals one end of the bell neck from the other, thus to prevent escape of air upwardly through the bell neck. As the lock washer 40 is provided with a flared or bell-shaped mouth, installation of the bell on the nozzle 28 is greatly expedited and the diver does not have to grope around in installing the bell on the nozzle.

One side of bell 36 is provided with a suitable boss 41, through the threaded bore of which extends the ignition device, illustratively a spark plug 42, a lock nut 43 being provided to lock the spark plug in place. The points 44 of the spark plug are positioned adjacent the jet 45 of mixed gases coming from pipe 32, but not so near as to be burned away when the jet is ignited. The other end of the spark plug has fastened thereto an electric cable 46 connected to a suitable source of current (not shown) and provided with a suitable switch (not shown) which when closed, ener-

gizes the spark plug to create a spark across its points.

In operation, when the diver's torch is extinguished, and he wishes to re-ignite it, he installs 5 bell 36 on the nozzle 28, as heretofore described, and then adjusts his air valve 22 (Figure 1) while holding bell 36 with its axis vertical, as shown in the drawing, until all of the water is driven out of the inside of the bell. At this time 10 the air valve may be closed so that the body of air within the bell is in a static condition. Thereafter the diver adjusts the oxygen and hydrogen valves to obtain the jet 45 of mixed oxygen and hydrogen. Thereafter the switch to 15 spark plug 42 may be closed, thus to ignite the jet. After this has been done, the diver may again adjust his air valve so that the flaming jet will not be extinguished when he removes bell 36 from the nozzle. Inasmuch as rubber 20 washer 39 seals the opposite ends of bell neck 37, air cannot flow upwardly through the bell neck during the ignition period, and accordingly the body of air within the bell is maintained static.

25 It will now appear that I have provided a device for igniting an oxygen-hydrogen torch under water which attains the several objects above set forth in a thoroughly practical and efficient manner.

30 As many possible embodiments may be made of the mechanical features of the above invention, and as the art herein described might be varied in various parts, all without departing 35 from the scope of the invention, it is to be understood that all matter hereinbefore set forth or shown in the accompanying drawing is to be interpreted as illustrative and not in a limiting sense.

40 I claim:

45 In apparatus for igniting a combustible mixture of gases under water, in combination, a torch having a nozzle for the flow of air and a combustible mixture of gases, a bell-shaped member having a neck extending therefrom, the diameter of said neck being greater than the diameter of said nozzle and the entrance end of 50 said neck being flared to an even greater diameter than the neck diameter, gasket means in said neck and adapted to tightly engage said nozzle when the nozzle is inserted into the neck when the bell member is attached to the nozzle, and ignition means secured to said bell member adjacent the outlet end of said nozzle.

55 MARIO DI ZOPPOLA.
